UNITED STATES PATENT OFFICE.

FREDERICK D. PHILP, OF ROYAL OAK, MICHIGAN, ASSIGNOR OF ONE-HALF TO ALLEN A. TEMPLETON, OF DETROIT, MICHIGAN.

PROCESS OF MANUFACTURING RUBBER HEELS OR SOLES.

1,230,510.

Specification of Letters Patent. Patented June 19, 1917.

Application filed August 17, 1916. Serial No. 115,398.

To all whom it may concern:

Be it known that I, FREDERICK D. PHILP, a citizen of the United States of America, residing at Royal Oak, in the county of Oakland and State of Michigan, have invented certain new and useful Improvements in Processes of Manufacturing Rubber Heels or Soles, of which the following is a specification, reference being had there-
10 in to the accompanying drawings.

This invention relates to a process of manufacturing rubber heels or soles and the invention is characterized by utilizing rubber considered as scrap, seconds, and of such
15 nature as useless for the purposes for which it was originally intended. A good example of such rubber are solid tires, and as the majority of solid vehicle tires are largely pure rubber and possess a high degree of
20 resiliency, such material is a desideratum in rubber heels and soles.

The primary object of my invention is to expeditiously and economically produce rubber heels and soles from discarded solid rubber tires, and the process by which I have produced heels and soles involves a plurality of operations or steps that insures a maximum number of heels or soles from the discarded rubber, with a minimum waste or
25 scrap, although such waste or scrap may be used for by-products.

Briefly considering the various operations, a tire is first cut into segments or pieces of a desired length and this cutting may be
35 performed by machine or hand. Second, a piece of the tire is flattened in a suitable holder with any rough or irregular surface of the tire exposed. Third, the piece of rubber while held in its holder is subjected
40 to the action of a grinder, for instance an emery wheel, so that the roughened surface of the piece of rubber may be ground down and irregularities removed therefrom. Fourth, the ground piece of rubber is divided longitudinally into slabs or strips of a predetermined thickness and this operation can be advantageously performed by sawing the rubber. A band saw may be used with a carriage that will hold and automatically feed the piece of rubber to the saw.
45 Fifth, the slab is punched or cut to provide a heel blank and the heel blank branded and apertured. All of these operations will be
50

hereinafter more fully considered, together with machine parts that may be used in producing heels or soles, and while I will herein principally refer to the production of heels, it is to be understood that soles can be as readily produced by the process.

In the drawings,

Fig. 1 is a perspective view of a piece of solid vehicle tire from which heels, in accordance with my invention, may be manufactured;

Fig. 2 is a perspective view of the same piece of tire after having the rough and irregular face thereof ground or planed;

Fig. 3 is an enlarged cross sectional view of the piece of tire divided into a plurality of slabs or strips;

Fig. 4 is a perspective view of a heel blank cut from one of the slabs or strips shown in Fig. 3;

Fig. 5 is a similar view of the same heel blank branded and marked;

Fig. 6 is a similar view of the branded and marked heel blank after it has been drilled, this view showing the completed article;

Fig. 7 is a plan of a heel die;

Fig. 8 is a vertical sectional view of the same showing a heel blank cut thereby in a slab;

Fig. 9 is a similar view showing the die retracted and the heel blank retained in the slab;

Fig. 10 is a side elevation of a grinding or planing machine that may be used for grinding or planing rough and irregular face of rubber shown in Fig. 1 to produce the smooth face shown in Fig. 2;

Fig. 11 is a plan of the machine, this view, as well as Fig. 10, showing a holder for a piece of rubber;

Fig. 12 is a bottom plan of a holder for the piece of rubber;

Fig. 13 is a cross sectional view of the same;

Fig. 14 is a plan of a portion of a band saw that may be employed for dividing a piece of rubber into slabs, as shown in Fig. 3;

Fig. 15 is a front elevation of a carriage forming part of the band saw;

Fig. 16 is a cross sectional view of the same;

Fig. 17 is a plan of the machine for simul-

2
taneously cutting, branding and drilling heels;

Fig. 18 is a front elevation of the same, and

Fig. 19 is a diagrammatic plan of an arrangement of machines by which my process may be expeditiously carried into effect.

In describing my process by aid of the views above referred to, I desire to point out that the same are merely illustrative, as an example, of machine elements and *modus operandi* by which my process may be carried into effect, and I do not care to confine myself to the machines or the precise product shown. The following description is therefore to be broadly construed as including such substitute devices and operation as are the mechanical or obvious equivalent of those to be hereinafter referred to.

As outlined in the general statement of my invention, I utilize the good rubber in discarded solid vehicle tires and often such tires are secured known as "seconds," which are in excellent condition and may eliminate the third step of my process, that of grinding or planing rough and irregular surfaces. However, a great many tires are received that have been stripped or cut from wheel rims, thereby leaving a tire with a rough and irregular face. The tire is cut into segmental pieces, either by hand or machine, and one of these pieces has been illustrated in Fig. 1 where it will be noted that the inner face 1 of the piece of rubber is ribbed, as at 2, and these ribs are simply an example of a rough or irregular inner face which prohibits the use of this particular face portion of the piece of rubber, until ground or planed off to present a smooth and uninterrupted face 3, as shown in Fig. 2.

The grinding or planing of the rough portion of the piece of rubber may be performed while the piece of rubber is in its natural segment shape, but I have found that such operation can be more expeditiously and accurately performed by flattening or distending the piece of rubber in a suitable holder and then subjecting the roughened portion of the piece of rubber to the action of a grinder or planer, for instance, a rough emery wheel.

In Figs. 10 to 13 inclusive, there are shown a holder and a machine by which the second and third operations, as heretofore briefly stated, may be performed. The holder comprises an oblong box 4 having an open side 5, somewhat similar to a miter box, and in this box is placed a longitudinal spacer member 6 upon which may be placed the outer rounded face of the segment piece of rubber. The piece of rubber is designated 7 and in using the term "outer face," I mean that face of the piece of rubber that was originally a part of the tread or periphery of a tire, and by referring to the

"inner face," it is to be understood that I mean that portion which was originally on or near the rim of a wheel. As tires vary in size, the spacer member 6 is made removable so that it may be replaced by a member 70 adapted for a special tire section. One of the walls of the box 4 has a plurality of set screws 8^a and the other wall a plurality of set screws 9 engaging a clamping bar 10, said bar coöperating with the set screws 8^b 75 in gripping or holding the piece of rubber 7 in the box. When placing the piece of rubber in the box pressure is brought to bear on the inner face of the piece of rubber, at the ends thereof, to force the ends down 80 into the box, whereby the piece of rubber may be gripped or clamped throughout its length to remain flat as possible within the box. The flattening or distending of the piece of rubber in the box may be manually 85 performed or by aid of clamps or other devices.

The piece of rubber is now in position to be ground or planed and for this purpose a planer 11 may be used having for its 90 planing instrumentality a rough emery wheel 12. The emery wheel 12 may be driven by a motor or from any suitable source of power, and the planer has an adjustable table 13 provided with an adjustable guide 14 against which may be shifted a flange 15 of the box 4, said flange providing clearance for the set screws 9. With the table 13 adjustable and the box 4 inverted thereon it is possible to regulate the 100 protrusion of the emery wheel 12 in the box, when said box is shifted over the emery wheel. Sometimes the condition of the inner face of the piece of rubber will require one or more passes of the same on 105 the planing machine, but as heretofore mentioned, when the inner face of the piece of rubber is in good condition and smooth as required for rubber heels, then the holder and the machine shown in Figs. 10 to 13 110 inclusive can be eliminated as contributing to the production of heels.

The next step or operation is that of dividing the piece of rubber 7 into slabs or strips 8, as shown in Fig. 3 and it is to be 115 noted that by flattening the pieces of rubber and holding them flat while dividing into slabs, that I obtain a large or maximum slab area. For instance, a segment shaped or curved piece of rubber, when horizontally 120 cut, will produce slabs varying in area or of different lengths, but when the piece of rubber is flattened prior to cutting, the slabs produced are of equal length and the width thereof varies as the cross sectional curvature of the tread portion of the piece of tire. Consequently there is a distinct advantage gained by flattening the curved pieces of rubber before dividing into slabs. I have found that the operation of producing slabs 125

can be best performed by an ordinary band saw provided with an especially designed carriage for holding the piece of rubber and feeding it to the band saw. In Figs. 14 to 16 inclusive there are illustrated the essential parts of an ordinary band saw, namely, a table 16 and the saw *per se*, which has been designated 17. The table 16 is provided with guides 18 for the slide members 19 of a track 20 and this track is preferably in the form of an angle bar with the vertical flange thereof constituting the track and in a plane parallel with the saw 17. The slide members 19 are provided with detents 21 to engage in the guides 18 and hold the track in adjusted positions, said detents constituting means whereby the track may be shifted transversely of the table 16 and provision may be made whereby the track may be automatically and intermittently fed toward the saw 17, for purposes which will presently appear. Suspended from the track 20 and maintained in spaced relation thereto is a carriage 22, preferably in the form of a channel bar which has the upper flange thereof provided with hangers 23 adapted to travel upon the track 20. The inner side of the carriage has spacing rollers 24 contiguous to the ends thereof and these rollers cooperate with the hangers 23 in detachably holding the carriage relative to the track and maintaining said carriage in parallelism therewith. That side of the carriage confronting the saw 17 is adapted to hold the strip of rubber 7, as best shown in Figs. 15 and 16, with the inner face of the piece of rubber snug against the outer face of the carriage. The lower edge of the carriage has permanent gripping members 25 and the upper edge of the carriage has adjustable gripping members 26, the said gripping members engaging the longitudinal edges of a piece of rubber and retaining it in snug engagement with the carriage. Both sets of gripping members may be made adjustable and simultaneously actuated to grip the longitudinal edges of a piece of rubber, but as shown, the carriage 22 can be removed, the piece of rubber flattened thereagainst, if not previously flattened, and then gripped by the members 25 and 26 whereby the piece of rubber will be positively held against accidental displacement.

Detachable relative to the outer end of the carriage 22 is a gravity carriage feeding device 27 in the form of a cable having a weight and this device is adapted to feed the carriage in one direction longitudinally of the table 16 so that the piece of rubber 7 will be carried into engagement with the saw 17. Adjacent the saw 17 is a stripper or deflector member 28, and assuming that the band saw is in operation and the carriage 22 loaded, as shown, the feeding device 27 shifts the piece of rubber 7 into engage-

ment with the saw 17. Figuratively speaking the saw passes longitudinally of the piece of rubber and removes the outer face thereof. The slab or strip is deflected away from the carriage by the member 28 and the first slab or strip removed may be considered scrap used in the manufacture of by-products. By restoring the carriage to normal position, the track 20 may be advanced toward the saw, a predetermined distance, so that another slab or strip may be cut from the piece of rubber. These operations are continuous until the piece of rubber has been divided into the desired number of slabs or strips that may be used in the production of heels; the depth of the heels determines the thickness of the slab, and the thickness of the slabs the number of slabs cut from a single piece of rubber.

During these operations it is preferable to lock the track 20 against accidental movement by clamping it on the table 16, as indicated at 29, but this arrangement may not be necessary when provision is made for automatically and intermittently moving the track relative to the saw.

While I have found sawing the best way to divide a piece of rubber into slabs or strips, one at a time, it is possible to use other means to accomplish the same result, or to simultaneously remove a plurality of slabs or strips from a single piece of rubber.

The rubber slabs or strips coming from the band saw are flat, on account of the length and thickness thereof, and do not tend to curve similar to the original piece of rubber, consequently the slabs or strips can be conveniently handled for the final operation, that of simultaneously punching, branding and drilling heels.

For the purpose of removing heel blanks from the rubber slab 8, a die 30 is employed in connection with a conventional form of punching machine 31. The hollow heel shaped and knife edge die 30, shown in Figs. 8 and 9 is intended for one size of heel and is one of many that may be used. The die has a hollow or tubular shank 32 for a spring pressed plunger 33, said plunger having a head 34 with a spring 35 for engaging said head. The expansive force of the spring 35 tends to force the plunger 33 outwardly and said plunger constitutes means within the die, for holding a heel blank 36 within the rubber slab 8 after the heel blank has been cut by the die 30.

The plunger head 34 may be heated and used as a branding iron, thereby combining the cutting and marking devices.

The die shank 32 is connected to the plunger 37 of the punch 31 in the usual and well known manner and the plunger 37 may be manually or automatically raised and lowered.

Adjacent the punch 31 is a branding and

75

95

100

105

110

115

120

125

130

marking device 38, having a reciprocable heated branding and marking iron 39, and gas or electricity may be employed for heating the iron.

- 5 In alignment with the punch 31 and the branding and marking device 38 is an ordinary drill 40 adapted to be operated by an electric motor 41 or from a suitable source of power. The drill 40 has a 10 multiple drill head 42 adapted to be raised and lowered, and in order that the punch 31, branding device 38 and drill 40, may be actuated in synchronism, a rock shaft 43 connects the three devices, and is 15 adapted, through the medium of pinions and racks, cranks or similar mechanism, to lower the die 30, the branding iron 39 and the drill head 42. The branding iron 39 is held normally elevated by a spring 44 associated with the plunger of the branding iron and the rock shaft 43 is provided with a weighted arm 45 adapted to hold the other two devices normally elevated. At one end of the rock shaft 43 is a hand lever 46 and 20 connections 47 with a treadle 48, thus permitting of the hand or foot being used to operate the devices in unison.

To carry the rubber slabs 8 into position to be operated on, an endless conveyer or belt 49 is employed and trained over pulleys 50 on shafts 51 and 52, journaled in suitable bearings 53, carried by a base frame 54. The base frame 54 supports an oblong table 55 under the upper strand of the conveyer or belt 49 to support the same during the operation of the three devices. The conveyer or belt 49 has a cover of non-penetratable or durable material, preferably in the form of closely arranged slats 56 of vulcanized rubber and it is upon these slats that the rubber slabs are placed, end to end, and detachably connected to the conveyer if necessary.

To intermittently move the conveyer 49 45 the shaft 52 is provided with a ratchet wheel 57 normally engaged by a gravity pawl 58, carried by an operating lever 59 loose on the shaft 52. The operating lever 59 is movable in front of a sector frame 60, carried by one of the bearings 53, and the sector frame 60 is provided with adjustable stop members 61 and 62. These stop members limit the movement of the lever 59 and consequently the intermittent advance of 55 the conveyer 49 beneath the three devices, but said stops can be adjusted whereby the conveyer 59 will have a desired movement and consequently properly place the rubber slabs 8 beneath the die 30, branding iron 39 60 and drill head 42.

Assuming that rubber slabs have been placed upon the conveyer, end to end, or that the three devices have been placed in such juxtaposition as to operate upon a 65 single slab, the die 30 will produce the heel

blank 36, shown in Fig. 4, and leave the same within the slab, as shown in Fig. 17. Simultaneous with this operation a heel blank is branded and marked, as suggested in Fig. 5, and another branded and marked heel blank 70 is drilled, as shown in Fig. 6 so as to provide the ordinary openings or apertures that receive nails or other fastening means when attaching the heel to a shoe.

The rubber slabs when leaving the drilling 75 machine 40 contain completed rubber heels which may be discharged in chutes 63 and carried by a conveyer 64 to a suitable packing place. These last two mentioned elements have been shown in Fig. 19 illustrating an arrangement of the various machine elements by which a large number of heels may be expeditiously manufactured. The slabs from which the finished heels have been removed may be used in the manufacture of 80 by-products or heels of a smaller size may be cut therefrom. For instance, by again referring to Fig. 17, it will be noted that small heels 65, commonly styled "Cuban heels" 85 furthermore, that it is possible to cut two sizes of heels by causing a greater number of machines to simultaneously operate upon the rubber slab.

As a substitute for the three machines, 31, 95 38 and 40, I desire to direct attention to the fact that rubber slabs may be placed in suitable jigs, and multiple die holders, multiple branding irons and multiple drill heads simultaneously or successively brought into 100 action to produce rubber heels in accordance with my invention.

From the foregoing, it will be observed that the process in its broadest aspect involves the production of shop heels and soles 105 from vulcanized rubber not originally intended for heels or soles, and in contradistinction to rubber and rubber compositions especially prepared, treated or made over for heels and soles. I am aware that rubber 110 heels and soles have been cut or shaped from rubber prior to the same being vulcanized, whereby my improved process specifically relates to the production of rubber heels and soles from rubber that has been previously 115 vulcanized. Besides tires, a great many other high grade pieces of rubber can be utilized, but I know of no commercial rubber possessing the resiliency and durability or otherwise as good as that rubber used in solid vehicle 120 tires, therefore I attach considerable importance to the fact that the heels are made solely from tires. A great many tires from which heels may be made must necessarily be trimmed to eliminate injured or irregular 125 portions, and throughout the various operations care is taken to prevent burning, crowding and such handling of the rubber as would cause the same to deteriorate or injure the natural surface of the rubber. 130

What I claim is:—

1. A process of manufacturing heels from rubber tires, consisting of dividing a tire into segment shaped pieces, holding the tire pieces in flat condition and while so held dividing the tire pieces into slabs, and punching the slabs to provide heel blanks. 5
2. A process of manufacturing heels from rubber tires, consisting of dividing a tire into segment shaped pieces, holding the tire pieces in flat condition and while so held removing irregular portions from the tire pieces, dividing the tire pieces into slabs, and punching the slabs to provide heel blanks. 10
3. A process of manufacturing heels from rubber tires, consisting of cutting a tire into segment shaped pieces, holding the tire pieces in a flat condition, dividing the tire pieces into slabs, punching the slabs to provide heel blanks, and successively branding and aperturing the heel blanks. 15
4. A process of manufacturing heels from rubber tires, consisting of dividing a tire into segment shaped pieces, holding the tire pieces in a flat condition, removing irregular portions of the tire pieces, dividing the tire pieces into slabs, punching the slabs to provide heel blanks, and successively branding and aperturing the heel blanks. 20
5. A process of manufacturing heels from rubber tires, consisting of cutting a tire into segment shaped pieces, holding the tire pieces in a flat condition and while so held dividing the tire pieces into slabs, punching the slabs to provide heel blanks, and branding the heel blanks while retaining them in the slabs. 25
6. A process of manufacturing heels from rubber tires, consisting of cutting a tire into segment shaped pieces, holding the tire pieces in a flat condition, dividing the tire pieces into slabs, punching the slabs to provide heel blanks, retaining the heel blanks in the slabs, and successively branding and aperturing the heel blanks while in the slabs. 30
7. A process of manufacturing heels from rubber tires, consisting of cutting a tire into segment shaped pieces, holding the tire pieces in a flat condition and while so held removing irregular portions of the tire pieces, dividing the tire pieces into slabs, punching the slabs to provide heel blanks, retaining the heel blanks in said slabs and then successively branding and aperturing the heel blanks in the slabs. 35
8. A process of manufacturing heels from rubber tires, consisting of dividing a tire into pieces, holding the tire pieces in flat condition and while so held removing irregular portions of the tire pieces and dividing them into slabs, punching the slabs to provide heel blanks, retaining the heel blanks in the slabs, and branding and marking the heel blanks while retained by the slabs. 40
9. A process of manufacturing heels from rubber tires, consisting of cutting a tire into pieces, holding the tire pieces in flat condition and while so held removing the irregular portions from the tire pieces and dividing them into slabs, punching the slabs to provide heel blanks, retaining the heel blanks in the slabs, branding and marking the heel blanks, and then drilling the heel blanks while so retained to provide apertures. 45
10. A process of manufacturing heels from rubber tires, consisting of cutting a tire into segment shaped pieces, holding the tire pieces in flat condition and while so held dividing them into slabs, punching the slabs to provide heel blanks, retaining the heel blanks in the slabs, branding the heel blanks while held by said slabs, drilling the heel blanks while held by said slabs, and then removing the heel blanks from the slabs. 50
11. A process of manufacturing heels from rubber tires, comprising cutting a tire into pieces, holding said pieces in flat condition, planing said pieces while so held, dividing said pieces longitudinally into slabs while so held, and then moving the slabs beneath a cutting die and cutting heel blanks therefrom. 55
12. A process of manufacturing heels from rubber tires, comprising cutting a tire into pieces, holding said pieces in flat condition, planing said pieces while so held, dividing said pieces longitudinally into slabs while so held, moving said slabs beneath a cutting die, cutting heel blanks therefrom, and then moving the heel blanks beneath branding irons and marking them thereby. 60
13. A process for manufacturing heels from rubber tires, comprising cutting a tire into pieces, holding said pieces in flat condition, planing said pieces while so held, sawing said pieces longitudinally into slabs while so held, moving said slabs beneath cutting dies, cutting heel blanks therefrom, moving the heel blanks beneath branding irons, marking them thereby and then moving the branded heel blanks beneath drills and aperturing them thereby. 65
14. A process of manufacturing heels from rubber tires, consisting of cutting a tire into pieces, flattening and securing the tire pieces in a holder, planing the tire pieces while held in the holder, removing the tire pieces from the holder and sawing said pieces to provide slabs, moving the slabs beneath dies, cutting heel blanks therein and then successively branding and aperturing the heel blanks. 70
15. A process of manufacturing heels from rubber tires, consisting of sawing the tire into slabs, intermittently moving the slabs and cutting heel blanks from the slabs. 75

and using the slabs as conveyers for the heel blanks, and marking and aperturing the heel blanks while in the slabs.

16. A process of manufacturing heels from vulcanized rubber consisting of removing irregular portions of the rubber, dividing the rubber into slabs, punching the slabs to provide heel blanks and leaving the heel blanks in the slabs and then successively 5 branding and aperturing the heel blanks in the slabs.

17. A process of manufacturing heels from rubber tires, comprising cutting the tire into slabs, moving the slabs beneath 10 cutting dies, cutting out heel blanks from the slabs, and using the slabs as conveyers to move the heel blanks from beneath the cutting dies to branding tools, branding the heel blanks, moving the heel blanks from

beneath said branding tools to aperturing tools, and aperturing the heel blanks thereby.

18. A process of manufacturing heels from a material previously used in manufacture for purposes other than that of 15 heels and in such form as to preclude the dividing the material into slabs of maximum area, comprising flexing the material to increase the slab area thereof, cutting slabs from the material while flexed, and then 20 cutting heel blanks from the slabs.

In testimony whereof I affix my signature in the presence of two witnesses.
